RADIORECEIVER

John P. Minton, White Plains, N. Y., assignor, by
mesne assignments, to said Minton and
Herbert H. Frost, New York, N. Y.

Application November 16, 1931, Serial No. 575,176

10 Claims. (Cl. 250—14)

This invention relates to improvements in radio receivers, and particularly to radio receivers of portable design and reduced size.

An object of the invention is to provide a radio receiver in the form of a compact, handy and complete unit; with all the necessary parts thereof, including a loud speaker, mounted upon a chassis, common support or base; the parts being conveniently arranged on the base and firmly 5 secured in position, so that the entire construction can be housed in a casing or cabinet by handling it as a whole to put it into the casing; and just as easily remove it therefrom.

A further object of the invention is to provide 15 a radio receiver of small compass with all the necessary parts thereof mounted upon a base or framework that is strong and rigid in construction, but exceedingly light and easy to make in the form required, to carry all of the parts and 20 to mount the loud speaker in central or other desired position.

In its preferred form the receiver has connections and appliances to enable it to be energized from a light or power circuit of a building; therefore batteries are not required and the 25 framework therefore bears not only the tubes, coils, condensers, loud speaker and other necessary elements, but also all the necessary means for converting power or lighting current into such 30 form so that it can be advantageously used to energize vacuum tubes and the coils of the loud speaker.

Other objects and advantages of the invention 35 are set forth in the ensuing description, taken with the accompanying drawings, which disclose a preferred embodiment of the invention. I do not, however, wish to limit myself to the exact 40 structure herein set forth, but reserve the right to make changes in various ways to the full extent which is consistent with the breadth of the 45 terms in which the appended claims are expressed and does not exceed the scope thereof.

On the drawings:

Fig. 1 is a front view of a radio receiving set 50 showing the support for the various parts in a suitable casing, the latter being shown in vertical section;

Fig. 2 is a top plan of the radio receiver with the casing shown in horizontal section; and

Fig. 3 is a transverse section on the line 3—3 of Fig. 1.

On the drawings the same numerals identify the same parts throughout.

To support the loud speaker, tubes, and other 55 members of the apparatus, I provide a frame-

work or chassis 1 of sheet metal in the form of a table or platform having a flat top, and the front and rear edges bent downward at 2 to stiffen and reenforce the top. At the ends are legs 3 which form part of the chassis and enable it to be stood upon any suitable supporting surface. Most of the parts of the radio set are mounted on the upper surface on the flat top of the base 1 but some are disposed beneath it and the loud speaker is preferably in central position adjacent a suitable opening in the front of the casing or cabinet for the set. 10

At one end of the base or chassis and on the top thereof are variable condensers 4 to tune the various stages; the movable elements of these 15 condensers being all attached to a common shaft 5 that projects through an opening in the front of the casing to receive a suitable operating knob. Hence by turning the knob, the shaft 5 is operated to adjust all of the condensers together. I 20 have illustrated three condensers, one behind the other from front to back of the apparatus and three tubes 6, one of which may be an audio frequency amplifier, similarly arranged on top of the support 1 besides the condenser 4. Adjacent 25 the other end of the chassis is the detector tube 7 and besides this tube is a rectifier tube 8. Both tubes 7 and 8 may be located towards the rear. In front of these tubes are a transformer 9 and a container 10 for electrical condensers. The 30 transformer 9 and the condensers in the container 10 are adapted to cooperate with the rectifier tube 8 to convert alternating current into smoothed-out direct current for the anodes of the tubes and to energize the cathodes thereof, or the 35 cathodes may be heated by alternating current if desired.

Adjacent the middle of the chassis there is a recess 11 in the top thereof to make room for the loud speaker indicated at 12. This loud 40 speaker comprises a vibrating diaphragm, the outer edge of which in combination with suitable packing 13 is secured between two rings 14, held fast to each other by screws or other securing 45 means. Two of these screws indicated, for example, at 15, affix the rings 14 to the front flange 2 of the chassis, this front flange being cut away in the middle as indicated at 16 to make clearance along with the recess 11 for the loud speaker 12. 50 When the chassis bearing the various necessary parts of the receiver is inserted into the casing or cabinet 17, the loud speaker will be disposed in registry with a central opening 18 in the front of the cabinet so that sounds reproduced by the 55

loud speaker can be transmitted without obstruction.

Preferably the cabinet 17 is closed at its sides, top, bottom and front, but open in back; so that the chassis 1 with the various parts thereon can be put into the receiver or taken out and the back of the receiver can be closed with a removable plate 19 which can be held in place in any feasible manner and taken out when desired.

10 The cabinet is provided with feet 20 and the rings 14 may be further supported by a foot in the form of an angle-plate 21 attached to the lower portion of these rings and to the bottom of the cabinet.

15 Supported from the lower side from top of the chassis 1 is a box 22 containing suitable condensers for the tube and other circuits of the set, this box having flanges for fastening screws. Adjacent the container 22 and below the top of the chassis 1 is also placed the iron core 23 of a transformer coil 24 which is to be in the output circuit of the detector 7. This iron core 23 is affixed to the lower end of a vertical bridge or yoke plate 25; having its ends bent to engage the rear ring 14 of the loud speaker and attached thereto in any suitable way and with its middle portion adjacent the rear of the conical diaphragm of the receiver 12, and with an opening therein for the connections between the diaphragm and the actuating armature. Just behind this bridge or yoke plate 25 is a magnetic yoke 26 anchored by means of bolts 27 to a plate 28 abutting and secured to the yoke 25. Within the yoke 26 are the operating coils of the loud speaker shown at 29, and to the rear of this member 26 is an angle-plate 30 secured to the member and to the chassis 2 to anchor the member 26 with the magnetic coils 29 therein. The angle-plate 30 also carries a ground terminal clip 31.

20 Adjacent the upper part of the bridge plate 25 is mounted the antenna condenser 32 which can be adjusted by the knob 33. To one side of the loud speaker is the switch 34 combined with the volume control device 35, which is manipulated by means of a shaft 36 extending through an opening 37 in the casing 17 and provided with a knob not shown at its outer end. A fixed plate 38 is secured to the chassis in front of the volume control device 35 and this plate carries at the upper end a bracket 39 to support the switch 34.

25 Rising from the end of the chassis adjacent the condensers 4 is a plate 40 affixed to the chassis, and connected to vertical transverse plates 41 which serve as partitions or shields between adjacent condensers 4 and provide compartments for each of the condensers. The end walls 42 for the front and rear condensers carry bearings for the shaft 5, and at 43 are connecting bars diagrammatically shown for the movable plates of the condensers. On the shaft 5 is a transparent dial 44 the face of which is marked with angular degrees of rotation 45 to indicate the position of adjustment of the condensers and these marks may show through a peep hole, not illustrated, in the front wall of the cabinet 17. At 46 is a lamp to illuminate this dial which may be of transparent or translucent material.

30 I also provide shields 47 between the vacuum tubes 6, these shields being in the form of metallic plates which are made fast to the plates 41 and extend vertically upward from the chassis, with a common hood or cap 48 engaging these shield plates 47 at the top.

In other words when the speaker is rigidly and directly connected with the chassis, which has considerable mass and all of its members rigid with one another, and when the speaker is not secured to the cabinet or casing 17, any vibrations of the diaphragm which might otherwise disturb the tubes are suppressed by the chassis. On the other hand if the speaker 12 were not rigidly and directly connected to the chassis, then the vibrations of the diaphragm would cause other vibrations in the set which would be transmitted through the various parts, and disturbance of the tubes as above described would result.

35 The conducting cord for connecting the set to a power circuit or wall socket is indicated at 49 and the antenna lead wire is shown at 50. Both of these leads pass out through suitable openings in the rear 19.

At 51 beneath the chassis 1 and attached thereto are hoods or chambers for the coils of the circuits associated with the condensers and tubes. 20 52 indicates an opening in the top 1 for the transformer 9.

30 The legs 3 of the chassis may be in the form of plates at the ends of the top 1 with side flanges 25 53 and bottom flanges 54 to reinforce and strengthen these plates and make them stiff enough to carry the weight of the set.

35 The entire construction and arrangement of the parts of the receiver are thus quite advantageous; and while the receiver is very compact, nevertheless all of the parts thereof are rendered very accessible for inspection, examination or repair. The various parts are held fast to the chassis by means of screws or the like and can 40 be taken off whenever necessary. The mere removal of the closure 19 permits the extraction of the entire radio from the cabinet and then any tube, coil, condenser or connection thereto can be given whatever attention is needed. Preferably the various conductors are mostly beneath the top of the chassis, although some may be above it and the set always presents a neat, ready and orderly appearance. As thus made up the set is unitary and complete and the loud 45 speaker is incorporated therewith instead of being separate and required to be connected by an outside cable.

Having described my invention, what I claim 50 is:

1. A radio receiver comprising a sheet metal chassis having a flat top and flanged along its front and rear edges, said chassis having an inward extending recess in its top and front flange, a loud speaker projecting into said recess and having its front substantially flush with the front of said chassis, and retaining rings at the front of the loud speaker affixed to the front flange at the sides of said recess.

2. A radio receiving set comprising a sheet 60 metal chassis having a flat top with flanged edges at the front and back and legs at the sides, the legs being attached to said flanged edges, tubes and condensers mounted on the upper surface of the chassis, a condenser casing and transformer below said top, the top also having an opening and a second transformer coil disposed in said opening, and a centrally located loud speaker at the front of the chassis and affixed theron.

3. A radio receiver comprising a chassis of sheet metal having a flat top with flanged front and rear edges and legs at the ends, said chassis having a central recess in its top adjacent the front, a loud speaker, means to hold the loud 75

speaker in the recess with its front substantially flush with the front of the chassis, and having at one side of the recess an opening for the coil of a transformer, the sides of said speaker being affixed to the flanged front edge of the top at the sides of the recess.

4. A radio receiver comprising a chassis having a flat top with a recess therein at the front, a loud speaker projecting into said recess and substantially flush with the front of the chassis, a vertical bridge plate attached to the loud speaker at its top and bottom and projecting into said recess, a magnetic yoke secured to the rear of said bridge plate, coils in said yoke for said speaker, and means for attaching said yoke to the chassis.

5. A radio receiver comprising a chassis with a flat top having a recess in front adjacent the center thereof, a loud speaker mounted on the top of the chassis and projecting into the recess and secured with its front substantially flush with the front of the chassis, a bridge plate rigid with the center of the chassis and attached to the rear of the loud speaker at the top and bottom thereof, and a variable antenna condenser mounted on said bridge plate.

6. A radio receiver comprising a chassis with a flat top having a central opening at its front, a loud speaker and a bridge plate projecting into said opening and holding the loud speaker in the recess with its front substantially flush with the front of the chassis and a transformer supported by the bridge plate below the top of the chassis, said bridge plate being secured to the inner end of said recess.

7. A radio receiver comprising a chassis with a flat top having its front and rear edges flanged and with legs at its ends, the front of the top being centrally recessed, a yoke affixed to the top at the inner end of the recess, a loud speaker at the open end of the recess and having its front substantially flush with the front of the

chassis, a coil in said yoke in the rear of said recess to operate the loud speaker, a bridge plate secured to the top and bottom of the loud speaker and projecting into the recess, a plate affixed to the rear of the bridge plate and anchor bolts 5 to secure the yoke and plate together.

8. A radio receiver comprising a chassis having a flat top, a loud speaker centrally mounted on the top of the chassis, the top of the chassis having a recess receiving a loud speaker, the front of the speaker being substantially flush with the front of the chassis and being secured to the top at the sides of the recess, means forming condenser compartments on said top at one side of the loud speaker, vacuum tubes on said top besides said condensers, vertical plates between said tubes, and a cap plate supported by said plates between said tubes.

9. A radio receiving set comprising a chassis supporting the various parts of the set thereon, 20 the chassis being of reenforced sheet metal having a flat top and supporting legs, the parts on said chassis comprising a loud speaker, the chassis having a recess in which the speaker is disposed with its front substantially flush with the front 25 of the chassis and secured to the top at the sides of the recess, a casing having a closed front, bottom, top and ends with an opening in front to register with the loud speaker when the chassis is inserted into the casing and a removable close- 30 sure plate for the rear of the casing.

10. A radio receiving set comprising a chassis, a condenser having a metallic enclosure on said chassis, a loud speaker on said chassis, amplifier tubes between the speaker and the condenser 35 and shielded on one side by the enclosure for the condenser and on the other by the parts of the loud speaker, said tubes also having shielding means over them and between them.

JOHN P. MINTON.
